MANUFACTURE OF BEET SUGAR

George E. Stevens, Denver, Colo., assignor to The
Western States Machine Company, New York,
N. Y., a corporation of Utah

Application July 12, 1938, Serial No. 218,727

10 Claims. (Cl. 127—62)

This invention relates to a new and improved process for the manufacture of sugar and, more particularly, to a process for the production of substantially pure crystals, or white sugar, and final molasses of low purity from the concentrated and partially purified syrup, or thick juice, obtained from the beet end operations and evaporators in conventional beet sugar manufacture.

Any process of sugar making is a process of eliminating non-sugars from a relatively impure starting material. The easier and more quickly the impurities can be segregated and removed from the stream of material being processed, the more efficient are refining operations. Three interrelated and variable factors enter into the efficiency of any particular process: the quality of the crystallized product, the purity of the end material discarded from process, and the effort expended in extracting the product and reducing the starting material to an end material that can be disposed of without undue loss of sugar values. In practice, the low value of sugar remaining in the end material, or final molasses, makes it necessary to select an end point of as low purity as practicable. The more direct the route to this point, the more savings are realized in intermediate steps and the less loss of sugar values in processing and filtering steps and through chemical changes during such steps.

The process now used to the greatest extent in beet sugar manufacture involves three boilings, or three stages of operation on massecuites of successively decreasing purities. The high purity, or white, boilings are made principally from evaporator thick juice and melted intermediate sugar, with added wash syrup from the white massecuite purgings which is of lower purity than either the thick juice or the melted sugar. The intermediate, or "high raw," boilings are made from green syrup produced at the white stage, to which a small amount of "machine syrup" is sometimes added from raw pan storage to "top off" the strike; and the low purity, or "low raw," boilings, after graining on green syrup from the white massecuite purgings, are completed with all the run-offs, the "machine syrup," produced at the intermediate stage. Raw sugar from the low purity boilings, at a purity of about 86 to 92, is generally sent to the low melter and thence back to first or second carbonation for partial purification and subsequent reintroduction into the head of the process with the incoming thick juice. The motor liquor purged from the raw massecuite is discarded as final molasses, at a purity of about 58 to 60.

In the conventional practice about 10-15% of the non-sugars present in the starting material are continually introduced back into the head of the process with the melted raw sugar, so that the work of segregating these non-sugars must be repeated and relatively large volumes of massecuite must be boiled in order to obtain a given yield and quality of product. Moreover, the quality of the product obtainable from the white pan boilings is definitely limited. If the purity of the white massecuite is made to exceed about 92 in an effort to raise the quality of the white sugar, the intermediate and raw massecuites become correspondingly higher than usual in purity, and the final molasses purged from the raw massecuite contains so much sugar that net yields are reduced to a point rendering the process less economical.

It is common practice to pass the wash syrup from the white massecuite purgings, because of its lower purity than the thick juice and melted intermediate sugar, through a separate blow-up tank, heater and filter before introducing it into the white pan boilings. In order to keep the white sugar purity at a suitable point the white massecuite is grained and boiled to fairly high crystallization before the wash syrup is added, but this changes the super-saturation of the massecuite, throws the temperatures and conditions of boiling out of adjustment, with resulting adverse effects on uniformity of grain size, and decreases the yield of white sugar per white massecuite boiling.

Furthermore, the practice of graining crystallizer massecuite on green syrup from the white massecuite purgings, which is often used to the extent of 20 to 25% of the low raw pan contents, has a tendency to raise the purity of the crystallizer massecuite above the point necessary to produce final molasses of minimum purity. Also, the addition of machine syrup to the grained pan at this stage of the process tends to produce uneven or "smear" grain, which interferes with proper crystallization and purging operations.

The only way heretofore available to attain purities higher than 92 at the white stage without excessive loss of sugar in the final molasses is to adopt a four-massecuite system comprising high-purity and low-purity intermediate boilings—a "high high raw" and a "low high raw" massecuite—the sugar from the high purity intermediate boiling being remelted and used as the footing for white massecuite. Such a system makes it necessary to boil and purge a much greater volume of massecuite for a given output of white sugar, the volume of intermediate

massecuite being more than doubled. This system has been tried recently in a beet sugar factory where it resulted in higher costs of operation, which off-set the sole advantage of a white product of higher quality.

5 An object of this invention is to provide a new and improved process for the manufacture of sugar which gives the optimum yield and quality of product combined with the minimum of expense and effort in producing the product and 10 segregating non-sugars into a low purity end material.

Another object is to provide an optimum 15 three-massecuite process for the manufacture of sugar from beets characterized by the maximum exclusion of non-sugars from the white side, with consequent recovery of white sugar of higher than ordinary quality, and the production of an end material, or final molasses, of desirably low 20 purity, the purity of the intermediate massecuite being controlled so as to provide the most efficient plant performance and prevent undesirable increases in raw side purity.

Another object of the invention is to provide 25 a process for producing beet sugar from evaporator thick juice in which all run-offs from centrifugals at stages where the sugar is washed in the centrifugals are continually fractionated into higher- and lower-purity fractions of controlled 30 purities, and in which such fractions and intermediate and raw sugars are constantly distributed so as to maintain constant control over the purity of the massecuites and more quickly and simply to concentrate and segregate non-sugars from 35 process than theretofore.

Another object is to adapt such a process for the best over-all efficiency under various conditions of operation, as when the thick juice is of 40 normal purity and when it is abnormally low in purity.

Still another object of the invention is to provide a process for making beet sugar in which the white pan boilings are continually supplied with melted raw sugar of considerably higher 45 purity than the normal white massecuite purity, while the crystallizer massecuite and the final molasses produced therefrom remain at no greater than their usual low purities.

A further object is to provide a three-massecuite process for the manufacture of beet sugar 50 in which each massecuite is boiled from a single standard liquor of controlled purity, the liquor for white massecuite being continually produced as a composite of incoming thick juice and process 55 materials of controlled purities and the liquors for intermediate and crystallizer massecuites being continually produced as composites of other process materials of controlled purities.

Among other objects of the invention are to 60 eliminate the usual separate treatment and boiling-in of wash syrup from white massecuite purgings, and to eliminate the graining of crystallizer massecuite on green syrup from white massecuite purgings, together with the disadvantages which 65 attend such practices.

Heretofore each stage of the sugar process has 70 generally been considered as a unit process from which to obtain crystals and relatively impure run-offs, and the purities of the several massecuites have been accepted as dictated by the character of the varying materials normally produced by these several unit processes and by the necessity of producing a low purity final molasses. I have departed from this concept and have found 75 that all benefits heretofore obtainable from the

perfection of boiling and purging operations at each stage may be realized, and that the efficiency of the whole process in respect of product quality and costs of manufacture may be greatly improved, by regulating the character of the materials produced at each stage and distributing them in the process so that the purities of the several boilings are kept under constant control and adjusted for the best performance of their individual and collective functions.

The preferred embodiment of my invention in the manufacture of beet sugar is an improved three-massecuite process including a high purity, or white, stage which yields the marketable product—white sugar—an intermediate stage, and a 10 low purity, or raw, stage which produces the end material—final molasses. The purity of the white massecuite is raised above normal by boiling it from the thick juice entering the process, to which has been added a large amount of melted 20 sugar, of considerably greater purity than the white massecuite, and a “high white” run-off fraction from the white centrifugals, of controlled purity substantially as great or greater than the white massecuite. A sharp separation 25 is made between centrifugal run-offs in the purging of the white massecuite so as to produce controlled purity “low white” and “high white” run-off fractions. The “low white” fraction is used as the principal material for the intermediate 30 stage of the process. The intermediate massecuite is regulated and kept at an abnormally low purity in relation to the purity of the white massecuite and at the point best suited for the production of a low-purity material for the crystallizer massecuite boilings by fractionating the 35 run-offs obtained in purging the intermediate massecuite into controlled “high intermediate” and “low-intermediate” fractions and returning the higher purity fraction to the intermediate 40 pan storage tank for combination with the “low white” fraction. The “low-intermediate” fraction represents the optimum available drop from the controlled intermediate massecuite purity and is passed to the raw pan for the production of 45 crystallizer massecuite of desirably low purity. The treatment of the crystallizer massecuite is carried out under uniform and accurate control so as to yield raw sugar of extraordinarily high 50 purity and separate centrifugal run-off fractions, one a “high raw” fraction of about the same purity as the “low intermediate” fraction, which is combined with the latter to form the liquor for crystallizer massecuite boilings, and another a final molasses of optimum low purity.

In the preferred practice, when the beets are not abnormally low in purity, this high purity raw sugar, as well as the intermediate sugar, is melted (dissolved) and passed directly to the blow-ups where it is combined with incoming thick juice. The purity of the white massecuite and, consequently, the quality of the white sugar are raised above conventional standards by this practice. Furthermore, the reintroduction of 60 large amounts of non-sugars into the process is avoided, the amount of white massecuite to boil for a given production of white sugar is materially reduced, and the total amount of all massecuites to be boiled per unit output of white sugar 65 is reduced, which mean a more direct route to the desired product, lower costs of manufacture, and less loss of sugar through process losses and chemical changes. The sending of melted raw sugar through carbonation and other treat- 70

ments prior to introduction into the head of the process is eliminated except under extraordinary circumstances.

In the accompanying drawings Figure 1 is an illustrative flow chart indicating the preferred manner of applying my invention to the manufacture of beet sugar. Figure 2 is an illustrative flow chart of another embodiment of the process, and Figure 3 illustrates a third embodiment of the process. The indications of units of equipment on these drawings are merely diagrammatic. It will be understood that one or more units of each piece of equipment may be used, depending upon the nature and capacity of the equipment and the character and volume of plant operations, and also that other equipment and operations which have no material bearing on the present invention may be present in any system for practicing the process.

The high purity, intermediate and low purity boilings take place in vacuum pans designated on the drawings by the characters A, B and C, respectively. The vacuum pans are supplied with footings from storage tanks A¹, B¹, C¹, respectively. The A and B pans discharge their strikes into mixers A² and B². The C pan discharges into crystallizer apparatus C², in which the crystallizer massecuite is cooled to promote the growth of crystals and the exhaustion of sucrose from the molasses, and from this the crystallized raw massecuite passes into a mixer C³. Each mixer supplies charges of massecuite to centrifugals, designated A⁴, B⁴ and C⁴ for the respective stages, in which the operations of purging mother liquor from sugar crystals, washing the crystals, and fractionating the run-offs into higher-and lower-purity fractions take place.

All of this equipment may be of known types of construction. It is important, however, that the mixers be equipped to permit accurate control over the consistency of the massecuite and to keep uniform the temperature and fluidity of successive charges as withdrawn for treatment in the centrifugals, which may best be accomplished, with maximum capacity and minimum dissolution of sugar grain, by use of the processes and apparatus described in my United States patents, Re-issue No. 20,556 and No. 2,086,951, respectively. It also is important to best performance that the centrifugals at each stage be capable of substantially uniform operation and of efficient elimination of syrups, that they be equipped with means for effecting a sharp separation between syrups flowing from the curb walls at different time intervals, and that the purging, washing and syrup-separating operations of each centrifugal cycle be kept under accurate and timed control and adapted for controlled variation to suit requirements when the qualities of the massecuite undergoing treatment are subject to change. Each centrifuging cycle on a given massecuite should involve a uniform period during which the sugar crystals are purged of substantially all of the mother liquor that can be eliminated efficiently by centrifugal force, a uniform time and period for applying controlled amounts of wash water after such purging, and a uniform time for actuating the syrup separating means. Centrifugal apparatus and processes possessing these features have been developed by Eugene Roberts and described in his issued patents and pending applications, and are now well known in the American sugar industry.

The sucrose-bearing starting or raw material for the process consists of evaporator thick juice, or, in a Steffens factory, evaporator thick juice and saccharate milk. In normal operations the evaporator thick juice is not combined with relatively impure melted sugar at first or second carbonation as in conventional practice; hence its purity is somewhat higher than in the practice of the usual beet sugar process. This material is passed through the blow-ups or receiving tank 10 and thence through heaters and filtration apparatus to the storage tank A¹. In addition, melted sugar and a "high white" run-off fraction consisting essentially of wash syrup from the white centrifugals, both of considerably greater purity 15 than the thick juice, are continually supplied to the tank A¹—preferably after using the high white fraction, with added hot water, to dissolve the washed intermediate and raw sugars in the "high melter," passing the materials together to the 20 same blow-ups, and flowing them through the same heaters and filtration equipment. The regular addition to the thick juice of large amounts of these materials of greater purity, from which all but a small proportion of non-sugars 25 has been eliminated, provides a single standard liquor for white massecuite boilings, results in a substantial increase in the purity of the white massecuite and permits a substantial improvement in the quality of the white sugar recovered 30 from the white stage operations.

The boilings at A are carried out in the known manner for white massecuite, and the massecuite is dropped from A into mixer A² from which charges of substantially uniform and controlled 35 fluidity are withdrawn successively for treatment in the white sugar centrifugals A⁴. The centrifugal operations are preferably kept uniform and under careful control and are of such nature as to effect rapid elimination of mother liquor, 40 or green syrup, from the sugar grain. The green syrup flowing from the curb of each centrifugal is collected in a trough A⁵ as the principal constituent of the "low white" run-off fraction. The sugar remaining in the centrifugals after a pre-determined period for expelling more than 90% of the green syrup is freed of the residual adhering mother liquor and impurities by the application of a clear liquid washing agent, such as 45 water. At a predetermined interval after applying the wash water the syrup separator is tripped to divert liquid flowing from the curb into a trough A⁶, so that wash syrup of predetermined and relatively high purity (substantially as high or higher than the white massecuite), is sharply 50 separated from the preceding syrup and collected separately as the "high white" fraction for recirculation to white pan storage at A¹. In this manner three materials of distinct and controlled 55 purities are produced from the white massecuite—white sugar of unusually high quality and two separate "high white" and "low white" run-off fractions, the first consisting essentially of wash syrup and the second consisting essentially of green syrup with a very small predetermined amount of wash syrup.

The "low white" fraction contains a large percentage of recoverable sucrose. With the white massecuite purity at a high point, above 92, the difference between its purity and the purity of the white massecuite is usually insufficient to keep the intermediate massecuite, which is made principally from this low white fraction, at a purity such that the intermediate run-offs will 75

produce a crystallizer massecuite of optimum low purity. According to my process, I maintain control over the purity of the intermediate massecuite and cause the mother liquor of the intermediate massecuite to stay at a purity best suited for the crystallizer massecuite boilings by continually combining the "low white" fraction with an intermediate run-off fraction of controlled purity so as to keep a standard liquor for intermediate boilings in the intermediate storage tank B¹.

Boilings are carried out at B on liquor from the storage tank B¹, and intermediate massecuite is dropped into the mixer B² and thence into centrifugals B⁴ for purging. Again, the fluidity of successive charges introduced into the centrifugals should be kept uniform and under careful control, and purging, washing and syrup separating operations at the intermediate centrifugals should be maintained under predetermined timed control.

Instead of effecting the syrup separation at the intermediate stage to produce a run-off fraction of very high purity, as preferably done at the white stage, a sharp separation between run-offs is effected to produce a "low intermediate" fraction, consisting of green syrup only, and a "high intermediate" fraction containing regulated proportions of green syrup and wash syrup. The proportion of green syrup depends upon the purity fixed for the crystallizer massecuite and the purity and volume of the low white fraction. In a Steffens factory the raw massecuite purity may be somewhat higher than in a non-Steffens factory without substantial economic effect on the process. With substantially uniform and efficient centrifugal operations, the purity of the high intermediate fraction is readily controlled by fixing the moment of actuation of the syrup separator in each centrifuging cycle so that after such actuation a substantially definite amount of green syrup flows into the trough B⁶, to be followed by the wash syrup after the wash water is applied. This high intermediate fraction is combined with the low white fraction at B¹ to provide liquor of controlled purity for intermediate massecuite boilings while the low intermediate fraction is passed to raw pan storage C¹ for boiling into raw, or crystallizer, massecuite at C.

The sugar produced at the intermediate stage ordinarily attains a purity of 98 to 99. It is passed to the high melter where it is dissolved in the high white fraction and added hot water, as mentioned above, and from the high melter it passes to the blow-ups for combination with the incoming thick juice.

At the raw stage of my process the pan liquor consists principally of the low intermediate run-off fraction. Under normal conditions of operation, as illustrated in Figure 1 of the drawings this is combined with a "high raw" run-off fraction, of about equal purity, produced at the raw centrifugals. The crystallizer massecuite boiled at C is dropped into crystallizer apparatus C² where it is cooled to promote additional crystallization of its sucrose content. From C² it is passed to a mixer C³ overlying the raw centrifugals C⁴. From the mixer, after treatment therein to increase their fluidity and render their consistency uniform, successive charges of the massecuite are introduced into the centrifugals. The purging of the uniformly conditioned charges of crystallizer massecuite is preferably carried out so as to attain a raw sugar purity much greater than heretofore obtained in known processes,

while avoiding any appreciable increase in final molasses purity. Each centrifugal is operated to effect maximum elimination of the green syrup within a substantially definite time interval. After such a time interval, the sugar remaining in the centrifugal is washed with a predetermined small volume of wash water. The centrifugal operations are preferably controlled so that the flow of mother liquor into the green syrup trough C⁵ is terminated at approximately the instant when the wash syrup is ready to enter this trough, and the wash syrup is then collected separately in a separate trough C⁶ as the high raw fraction which is taken to the storage tank C¹. With uniform heat conditioning of the raw massecuite before centrifuging according to the process of my U. S. Patent Reissue No. 20,556, and with efficient and uniform centrifugal operations and accurate syrup separation, I have found it possible in normal operations to wash the raw sugar in the centrifugals to a purity of 97 to 99 while separating the wash syrup sharply from the mother liquor and producing final molasses of as low or lower purity than obtainable in the usual process where no washing is employed. Should the purity of the low intermediate fraction entering the raw stage, under special circumstances, be too high for proper raw stage operations, a predetermined proportion of green syrup may be collected with the wash syrup in the trough C⁶ and returned to tank C¹, thus keeping the raw massecuite purity at the proper point and preventing any undesirable increase in final molasses purity.

The raw sugar of 97 to 99 purity obtained from the low purity stage of operations contains relatively little of non-sugars. The major portion of the non-sugars have been segregated and diverted from the process in the final molasses. Most of the residual non-sugars which normally would be present in the raw sugar have been removed in the high raw fraction, which is of about the same purity as the raw massecuite and is returned to the raw pan with the low intermediate fraction for extraction of its sugar. The washed raw sugar is passed directly to the high melter, where it is dissolved in the same manner as the intermediate sugar, and from the high melter it is passed as part of a sugar solution of relatively high purity to the blow-ups for combination with incoming thick juice and reentrance into the head of the process.

The process substantially as described above provides the best combination of high product quality, low final molasses purity and low costs of operation in beet sugar making when the non-sugar content, such as sulfates and gums, in the thick juice is not abnormally high. When poor quality beets keep the white massecuite purity much below normal and when the raw massecuite is boiled or crystallized improperly or for any other reason is of a quality preventing effective washing to high purity, the raw sugar is preferably discharged from the centrifugals at C⁴ without washing, and this unwashed raw sugar of low purity (about 88-92) is preferably dissolved in the low melter, in a portion of the low white fraction diluted with hot water, and then taken to intermediate storage, as indicated by the flow chart in Figure 2 of the drawings. In this way the impurities in the raw sugar are short-circuited out of the process and the quality of the intermediate massecuites raised above its abnormally low point, with resulting benefits in respect.

of white massecuite purity and volume of boilings.

When operations at the raw stage are carried out such that the purity of the washed raw sugar remains considerably below normal, for example, below about 96 yet much higher than the intermediate massecuite purity, or when the washed raw sugar is of abnormally high sulfate content, it may be preferable to modify the distribution 10 of the raw sugar in the process, as indicated by the flow-chart in Figure 3 of the drawings, passing it to the low melter, where it is dissolved in hot water or hot "sweet water," and then to first or second carbonation for partial purification and subsequent reintroduction into the head of the process.

My process, as normally practiced, provides an optimum three-massecuite system for making beet sugar. It involves the formation of three 20 standard liquors for pan boilings, each of which is a predetermined composite of materials of controlled purity. The white massecuite, at the head of the process, is constantly maintained at a very high purity and produces white sugar of a very high quality. The crystallizer massecuite, at the final stage of the process, produces an end material characterized by optimum exhaustion of sucrose. Between these two lies an intermediate massecuite, the purity of 30 which is controlled by fractionation and distribution of run-offs so that increases in the purity of the raw massecuite which otherwise would result from the high white massecuite purity are avoided. The optimum segregation of sugars and non-sugars consistent with this type of operation is effected at each stage, and the distribution of materials is carried out so that the directness and economy of the route from starting material to white sugar of high quality are 40 greatly improved.

The significance of my process may be gathered in part from the following tabulation of data representing, on the one hand, average results of beet sugar processes which follow the 45 general three-boiling practice mentioned hereinabove, and on the other hand, approximate results which may be obtained by the full use of the present invention. These data are based upon the processing of thick juice of the same 50 quality. They are presented only by way of illustration, since the specific figures will vary in practice, depending upon the quality of beets, operating conditions, operating supervision, etc.

WHITE STAGE	
Prior practice	
I. White massecuite components.	I. White massecuite components.
A. Thick juice and melted sugar from blow-ups, heaters and filters, 90-92 purity, consisting of:	A single liquor, supplied continually from blow-ups, heaters and filters, consisting of:
(1) Evaporator thick juice, 92 purity, plus melted raw sugar from low melter, at 87-90 purity, added at 1st or 2nd carbonation, 89-91 purity.	(1) Evaporator thick juice, 92 purity, 66
(2) Melted intermediate sugar, from "high melter," 94-96 purity.	(2) Liquor from high melter, 97 purity, 34 including:
B. Wash syrup from white purgings, after treatment in special blow-ups, heaters and filters, 87-89 purity.	(a) Intermediate sugar, 99 purity, 16
White massecuite=A+B, 89-91 purity.	(b) Raw sugar, 98 purity, 8
	(c) High white fraction, 94 purity, 10
	White massecuite from above liquor, 94 purity.

INTERMEDIATE STAGE	
II. Intermediate massecuite components.	II. Intermediate massecuite components.
A. Green syrup from white purgings, 82-85 purity.	A single liquor from intermediate pan storage, consisting of:
B. Machine syrup from low raw pan storage, 71-74 purity.	(1) Low white fraction, 87 purity, 70
Intermediate massecuite=100% A, 82-85 purity or (occasionally), A+B, 84-84 purity.	(2) High intermediate fraction, 78 purity, 30
	Intermediate massecuite from above liquor, 84 purity.

FINAL STAGE	
Prior practice	New practice
III. Crystallizer massecuite components	III. Crystallizer massecuite components.
A. Green syrup from white purgings, to grain pan, 82-85 purity.	A single liquor from low raw pan storage, consisting of:
B. Machine syrup from intermediate purgings, 71-74 purity.	(1) Low intermediate fraction, 74 purity, 90
Crystallizer massecuite=A+B, 72-75 purity.	(2) High raw fraction, 74 purity, 10
IV. Final molasses purity 58-60.	Crystallizer massecuite from above liquor, 74 purity.
	IV. Final molasses purity 58.

The invention is not restricted to the details 25 of embodiments described hereinabove for purposes of illustration, but extends to other practical embodiments utilizing its novel features as set forth in the appended claims.

I claim:

1. In the processing of white beet sugar and final molasses from evaporator thick juice by a succession of massecuite-boiling and centrifuging operations in three stages at successively lower purities, the steps which comprise washing the sugar in centrifugals at each stage to purities greater than the highest massecuite purity, separating centrifugal run-offs at each stage into higher-purity and lower-purity fractions of predetermined controlled purities, returning the 30 higher purity fractions for boiling into massecuites at the respective stages, withdrawing the lower purity fraction at the lowest stage from process as final molasses, passing the lower purity fractions from the other stages to the stages 35 next below for boiling into massecuite, melting the washed sugar from the intermediate stage and passing the same to the highest purity stage for boiling into white massecuite, melting the washed sugar from the lowest stage and passing 40 the same to a higher purity stage for boiling into massecuite, and withdrawing the washed sugar from the highest purity stage from process as 45 the white beet sugar product.

2. In the processing of white beet sugar and 50 final molasses from evaporator thick juice by a succession of massecuite-boiling and centrifuging operations in three stages at successively lower purities, the steps which comprise purging and washing the sugar in the centrifugals at 55 the lowest, or raw, stage to a purity above the white massecuite purity, separating raw centrifugal run-offs into a higher-purity fraction of a purity near the raw massecuite purity, consisting essentially of wash syrup, and a lower-purity fraction consisting substantially entirely of green syrup, withdrawing the lower-purity fraction from process as final molasses of optimum low purity, dissolving the washed raw sugar and recirculating the same into a higher purity 60 stage of the process, and returning said higher purity fraction for boiling into further strikes of raw massecuite.

3. In the processing of white beet sugar and 65 final molasses from evaporator thick juice by a 70

75

- succession of massecuite-boiling and centrifuging operations in three stages at successively low purities, the steps which comprise fixing the purity of the lowest massecuite for the production 5 of mother liquor of optimum low purity to be removed from the process as final molasses, keeping the highest massecuite at the optimum purity for the production of high-quality white sugar, washing the highest sugar and separating 10 centrifugal run-offs into a high white fraction consisting substantially entirely of wash syrup of a purity at least as high as the white massecuite and a low white fraction consisting essentially of green syrup, washing the sugar at the 15 intermediate stage and separating centrifugal run-offs into a high intermediate fraction and a low intermediate fraction consisting substantially entirely of green syrup, combining said high intermediate fraction with said low white fraction 20 and boiling massecuite at said intermediate stage therefrom, controlling the purity of the high intermediate fraction in relation to the purity of the low white fraction to keep said intermediate massecuite at normal purity in relation to 25 said lowest massecuite, boiling said low intermediate fraction into said lowest massecuite, melting the washed sugar from the intermediate stage and passing the same to the highest stage for boiling into white massecuite and melting 30 the sugar produced from the lowest massecuite and passing the same to a higher purity stage for boiling into massecuite.

4. In the processing of white beet sugar and final molasses from evaporator thick juice by a 35 succession of massecuite-boiling and centrifuging operations in three stages at successively lower purities, the steps which comprise washing the sugar in centrifugals at each stage to purities greater than the highest massecuite purity, separating centrifugal run-offs at each stage into higher-purity and lower-purity fractions of predetermined controlled purities, returning the higher purity fractions for boiling into massecuites at the respective stages, withdrawing the 40 lower purity fraction at the lowest stage from process as final molasses, passing the lower purity fractions from the other stages to the stages next below for boiling into massecuite, dissolving washed sugar from all but the highest stage, introducing the dissolved washed sugar into the 45 highest stage for boiling into massecuite with the higher purity fraction from said stage and with incoming thick juice, and withdrawing the washed sugar at the highest stage from process as white sugar of high quality.

5. In the processing of white beet sugar and final molasses from evaporator thick juice by a succession of massecuite-boiling and centrifuging operations in three stages at successively 50 lower purities, the steps which comprise purging and washing the sugar in the centrifugals at the lowest, or raw, stage to a purity of at least 96, separating raw centrifugal run-offs into a higher purity fraction of a purity near the raw 55 massecuite purity, consisting essentially of wash syrup, and a lower purity fraction consisting substantially entirely of green syrup, withdrawing the lower purity fraction from process as final molasses of optimum low purity, dissolving said 60 washed raw sugar, passing the dissolved raw sugar to the highest stage for boiling directly into white massecuite, and returning said higher purity fraction for boiling into further strikes of raw massecuite.

- 75 6. A three-massecuite process for producing

white beet sugar and final molasses from evaporator thick juice, which comprises fixing the purity of the raw, or crystallizer, massecuite for the production of final molasses of optimum low purity, boiling the white massecuite from incoming thick juice and continually added process materials of considerably greater purity than the thick juice including a controlled run-off fraction from the white purgings and dissolved washed sugar, maintaining the intermediate 10 massecuite at a normal purity in relation to the fixed purity of the raw massecuite and at an abnormally low purity in relation to the purity of the white massecuite by including therein a run-off fraction of predetermined purity and volume 15 from the intermediate purgings, boiling said raw massecuite principally from a run-off fraction consisting of green syrup from the intermediate purgings, melting the sugar from said intermediate massecuite and recirculating the same for 20 boiling into white massecuite and melting the sugar from said raw massecuite and recirculating the same for boiling into massecuite of higher purity than said raw massecuite.

7. A three-massecuite process for producing 25 white beet sugar and final molasses from evaporator thick juice which comprises fixing the purity of the raw, or crystallizer, massecuite for the production of final molasses of optimum low purity, washing the sugar from each massecuite 30 in centrifugals, boiling the white massecuite from the incoming thick juice and added process materials of considerably greater purity than the thick juice including a run-off fraction consisting substantially entirely of wash syrup from the 35 white purgings and dissolved washed sugar, maintaining the intermediate massecuite at a normal purity in relation to the fixed purity of the raw massecuite and at an abnormally low purity in relation to the purity of the white massecuite 40 by boiling the same from a run-off fraction consisting essentially of green syrup from the white purgings and a run-off fraction from the intermediate purgings consisting of predetermined proportions of green and wash syrups, boiling 45 said raw massecuite from a run-off fraction consisting of green syrup from the intermediate purgings and a run-off fraction consisting essentially of the wash syrup from the raw purgings and dissolving washed intermediate and raw 50 sugars and adding them to incoming thick juice as aforesaid.

8. A three-massecuite process for producing white beet sugar and final molasses from evaporator thick juice which comprises fixing the 55 purity of the raw massecuite for the production of mother liquor of optimum low purity to be removed from the process as the final molasses, washing the sugar from each massecuite in centrifugals to a purity greater than the white 60 massecuite purity, separating centrifugal run-offs from each massecuite into higher-purity and lower-purity fractions of predetermined controlled purities, returning the higher-purity fractions for boiling into massecuites at the respective stages, combining the lower-purity white and intermediate fractions, respectively, with the higher-purity intermediate and raw fractions and boiling intermediate and raw massecuites from the respective combined materials, withdrawing 65 the lower-purity raw fraction from process as the final molasses, dissolving washed intermediate and raw sugars, combining said washed sugars with the higher-purity white fraction and with incoming thick juice and boiling the white massecuite 70

75

quite therefrom, withdrawing washed white sugar crystals of high quality from process, and controlling the purity of the higher-purity intermediate fraction in relation to the volume and purity of the lower-purity white fraction to maintain the intermediate massecuite at a normal purity in relation to the fixed purity of the raw massecuite and at an abnormally low purity in relation to the white massecuite.

10. 9. A three-massecuite process for producing white beet sugar and final molasses from evaporator thick juice which comprises fixing the purity of the raw, or crystallizer massecuite for the production of final molasses of optimum low purity, boiling the white massecuite from the incoming thick juice and added process materials of considerably greater purity than the thick juice including a run-off fraction consisting substantially entirely of wash syrup from the white purgings and dissolved washed sugar, boiling said raw massecuite from a run-off fraction consisting of green syrup from the intermediate purgings, purging said raw massecuite to produce the final molasses and unwashed raw sugar, dissolving the raw sugar, maintaining the intermediate massecuite at a normal purity in relation to the fixed purity of the raw massecuite and at an abnormally low purity in relation to the purity of the white massecuite by boiling the same from dis-

solved raw sugar together with a run-off fraction consisting essentially of green syrup from the white purgings and a run-off fraction from the intermediate purgings consisting of predetermined proportions of green and wash syrups, 5 and dissolving washed intermediate sugar and adding it to incoming thick juice as aforesaid.

10. In a three-massecuite process for the production of white beet sugar and final molasses from evaporator thick juice, the steps which comprise boiling the white massecuite only from thick juice and process materials of greater purity than the thick juice and thus maintaining the white massecuite at a purity of at least 92, boiling the intermediate massecuite from process 15 materials including green syrup from the white massecuite purgings and a special run-off of controlled purity from the intermediate massecuite purgings, producing said special run-off by combining wash syrup and green syrup from the intermediate purgings in proportions regulated to maintain the intermediate massecuite at an abnormally low purity in relation to the white massecuite purity and at a normal purity in relation to the lowest purity, or raw, massecuite, 25 and passing the remainder of the green syrup from the intermediate purgings to the lowest purity stage for boiling into raw massecuite.

GEORGE E. STEVENS.
